WIRE TIGHTENER

Evin R. Ferguson, Mitchell, Nebr.

Application April 24, 1934, Serial No. 722,178

4 Claims. (Cl. 254—188)

This invention relates to wire pulling devices and more particularly to a puller or tightener which is so constructed that it can be readily adjusted after being initially tightened so that the 5 wire can be additionally tightened without releasing the partially tightened wire.

An object of this invention is to provide a tightener or puller of this type which embodies a plurality of tackle blocks or sheaves having an 10 elongated rope engaged therewith in a manner so that the rope may be pulled and gripped or clamped in a manner that if the free end of the rope is loosened, the wire, which is partially tightened, will not become loosened, thereby permitting 15 an adjustment of several of the blocks or sheaves relative to each other so that the wire may be additionally tightened without slackening the partially tightened wire.

Another object of this invention is to provide 20 in a device of this kind means whereby the rope holder can be readily moved to released position so that the rope may be loosened after the wire has been suitably tightened.

The above and various other objects and advantages 25 of this invention will in part be described and in part be understood from the following detailed description of the present preferred embodiment, the same being illustrated in the accompanying drawings wherein:—

30 Figure 1 is a detail side elevation of a device constructed according to the preferred embodiment of this invention.

Figure 2 is a plan view partly broken away.

Figure 3 is a fragmentary sectional view of one 35 of the end sheaves or blocks with the side plate removed therefrom and the rope holder in clamped position.

Figure 4 is a view similar to Figure 3 but with the rope holder in released position.

40 Figure 5 is a diagrammatic view showing how the rope is trained over the sheaves or blocks.

Figure 6 is a fragmentary side elevation of a rope holder or clamp secured to another of the blocks.

45 Figure 7 is a detail side elevation of a different type of rope clamp or holder which may be used in connection with this invention.

Referring to the drawings wherein like numerals of reference designate corresponding parts 50 throughout the several views, the numeral 10 designates generally a sheave or block provided with a U-shaped clevis 11 having a hook 13 secured to the central portion thereof. A second sheave or block 12 having a clevis or U-shaped member 14 provided with a hook 15 is disposed

in spaced relation to the block or sheave 10 and a length of rope 16 is trained over the pulleys comprising the sheaves 10 and 12, as will be hereinafter described.

The sheave or block 10 comprises a pair of 60 inner spaced plates 17 between which an intermediate pulley 18 is rotatably carried by a shaft 19. The plates 17 are spaced apart by means of spacing members 20 and in the present instance, are of substantially triangular configuration with 65 a pin 21 engaging through the two plates at the inner end thereof at one side and a second pin 22 engaging the two plates 17 at the opposite side from the pin 21. A pair of outer pulleys 23 and 24 are mounted on the shaft 19 on opposite sides 70 of the middle or intermediate pulley 18 and plates 25 and 26, respectively, engage against the outer face of the pulleys 23 and 24.

The block or sheave 12 comprises side plates 27 having a pair of spaced shafts 28 and 29 disposed 75 therethrough on which are mounted pulleys 30 and 31, respectively. An intermediate or pulling sheave or block, generally designated as 32, is disposed between the two blocks 10 and 12, and comprises a pair of intermediate plates 33 disposed 80 in spaced relation to each other which have a shaft 34 extending therethrough. An intermediate pulley 35 is journaled on the shaft 34 and on opposite sides of the intermediate plates 33, there are pulleys 36 and 37 which are also 85 journaled on the shaft 34. Outside plates 38 and 39 engage against the outer side of the pulleys 36 and 37.

The intermediate plates 33 are relatively wider than the outer plates 38 and 39, being provided 90 with lateral extensions 40 and 41. An idler pulley 42 is journaled between the extensions 40 in spaced relation to the shaft 34, and a second idler pulley 43 is journaled between the extensions 41 at a point opposed to the first idler pulley 42. 95 A third idler pulley in the form of a tightening member 44 is journaled between the intermediate plates 33 at a point spaced longitudinally from the pulley 35.

The rope 16 has a loop 45 at one end which is 100 engaged about the pin 21 in the block or sheave 10 and the rope is then extended in the direction of the sheave or block 12 with the length 46 of this rope trained over the pulley 30. The rope is then continued as by length 47 and passed over 105 the idler pulley member 44 and then returned as by length 48 to the pulley 31 over which it is trained, and the length 49 is then extended in the direction of the first block 10 being trained over the idler pulley 43 and then looped over a 110

clamping hook, generally designated as 50, which is mounted on the pin 22 in the block 10.

As will be more specifically indicated in Fig. 6, this hook or holding member 50 permits the adjustment, either the lengthening or the shortening of the length of rope 49, and comprises a bar 51 having a hook 52 directed rearwardly or in the direction of the pin 22 and a second fixed hook 53 spaced laterally from the hook 52 but 10 directed forwardly. A swinging hook or locking member 54 is pivotally mounted on the bar 51 and coacts with the two hook members 52 and 53, which constitute fixed clamping members to releasably clamp the looped rope passing through 15 the hook member 50. This hook 54 has the looped portion thereof directed rearwardly or in the same direction as the rear fixed hooked member 52.

After passing through the hook 50, the rope 16 is continued with the length 55 extending in the 20 direction of the pulling sheave 32 and is trained over the outer pulley 37 and then continued as by length 56 in the direction of the sheave 10, and the rope is then trained over the pulley 26 and continued as by length 57 in the direction 25 of the sheave 32, being trained over the pulley 35. The rope is then continued as by length 58 in the direction of the sheave 10, being trained over the pulley 18 and then continued further as by length 59 in the direction of the pulling sheave 32 where 30 it is trained over the pulley 36. The rope is continued further as by length 60 in the direction of the sheave 10 and is trained over the outer pulley 23, and the rope may be continued for any desired length with the remaining portion of the 35 rope free so that the three sheaves or blocks may be separated for the desired distance so that the wire or other means connected to one of the outer blocks or sheaves will be tightened, as may be desired.

40 When it is desired to tighten a length of wire, the hook 13 may be secured as by a chain or rope or other means to a fixed member in the form of a post or the like, and the hook 15 may be secured to an end of the wire or member to be 45 tightened. The free portion 61 of the rope 16 is then pulled and this will tend to draw the intermediate sheave 32 toward the rear sheave 10. Movement of the sheave 32 toward the sheave 10 will cause the lengths 46 and 49 of the rope to 50 be shortened by reason of the movement of the pulling idler 44 in the direction of the sheave 10.

After the intermediate or pulling sheave 32 has moved to a point relatively close to the fixed or rear sheave 10, a rope holding member, generally 55 designated as 62, carried by the sheave 12 is moved to operative or clamping position so that the length 46 of the rope will not be slackened and in like manner, the sheave 12 cannot move relative to the sheave 10. At this time, the free end 61 of the rope can be released so as to loosen the lengths of the rope which are trained over the pulleys carried by the sheaves 10 and 32, thereby permitting the pulling or intermediate sheave 32 to be moved forwardly in the direction of the 65 forward sheave 12. When this movement takes place, the lengths 47, 48 and 49 of the rope will be slackened but the clamping hook 54 can be swung to released position so that this slack may be initially taken up and the hook 54 then swung 70 into clamping position when the length 49 is substantially equal to the length 46. The free end 61 of the rope can be pulled again and the pulling or intermediate sheave 32 moved toward the rear sheave 10, as hereinbefore described.

75 The rope holding member 62 comprises a U-

shaped member 63 provided with forwardly extending slotted arms 64 loosely engaging over a pin 65 carried by the side plates 27. A rocking rope holding member 66 is mounted on a pin 67 carried by the free legs of the U-shaped member 63 and is spaced from the bight of the member 63 a distance sufficient that when in released position, the rope 16 will readily move between the inner surface of this cam-shaped member 66 and the bight of the member 63. An extension 68 is carried by the cam-shaped member 66 extending in the direction of the pulley 30, and when the rope holding member 62 is in clamping position, as shown in Figure 3, the extension 68 is raised and the U-shaped plate 63 is moved forwardly a distance such that the extension 68 will constitute a lever engaging against the groove of the pulley 30 and acting to press the eccentric portion of the member 66 against the rope 16 so as to tighten this rope within the holding member 62. The greater the strain applied to the sheave 12, the greater the pressure will be applied to the rope 16 by the clamping member 66.

When it is desired to release the holder 62, the U-shaped member 63 is moved rearwardly and the lever or extension 68 is swung inwardly to a position, as shown in Figure 4, being held in this position by means of a transversely extending pin 69 carried by the lever 68, which engages the rear ends of the arms 64. In this position, the rope 16 is free to move forwardly through the holding member 66. After the wire has been tightened to the desired degree, it can be held in this position not only by the holding member 62, but the free end 61 of the rope 16 may be locked or held 105 by means of a rope holding member 70 which is carried by the rear sheave 10. This rope holding member 60 has a cam-shaped clamping member 71 which is provided with a releasing hook 72. The holding member 70 is mounted on a pin 73 115 carried by the block or sheave 10 and the pin 73 is engaged by a pair of slotted arms 74 integral with the U-shaped plate 75 which has the cam member 71 mounted therebetween.

It will be apparent from the foregoing that an 120 exceedingly simple but at the same time practical wire tightener or puller has been provided whereby the wire or member to be tightened will be held in its initial and partially tightened position until the device is re-set so that an additional tightening operation may be performed which, as hereinbefore described, may be performed without having any slack in the member to be tightened. The holding member 62 is automatic in its operation and when the wire or device is being tightened, the holding member 62 is in substantially the position shown in Figure 3, so that the cam and serrated inner face portion of the member 66 will drag on the periphery of the rope passing through the holder 62. By reason of the plurality of pulleys carried by the block or sheave 10 and the pulling block or sheave 32, a relatively great amount of power may be applied to the pulling operation by an individual thereby making it unnecessary to use a machine 130 or other tightening means in order to pull the desired article until it has reached the desired tension. It will be apparent that this device can be used for building of fences, pulling of cables, pipes or other means and I, therefore, do not wish to be limited to the use of this article merely as a 135 pulling means for fence wire, as it is obvious that the device may be used for other purposes where great power is desired from manual effort.

140 A different form of holding member is dis- 145

closed in Figure 7 wherein there is shown a plate 76 having a slotted arm or extension 77. This plate 76 is slotted, as at 78, and a serrated wheel or rope clamping member 79 is mounted on a 5 shaft 80 which is slideable in the slot 78. A fixed serrated jaw 81 is disposed in confronting relation to the periphery of the rotatable clamping member 79. The slot 78 in the plate 76 is disposed on an angle to the adjacent face of the 10 clamping member 81, so that as the rotatable clamping member 79 moves forwardly in the slot 78, it will move closer to the confronting face of the clamping member 81. This clamp or holder shown in Figure 7 is designed for use on the 15 hock 15 to hold barbed wire to be tightened by the tightening means hereinbefore described.

What is claimed is:—

1. A wire stretching means comprising a pair of sheave members each including a plurality of 20 pulleys, an intermediate sheave having a plurality of pulleys, idling pulleys carried by said intermediate sheave, a rope having one end secured to one of said pair of sheave members and engaging over one pulley of the other sheave, said 25 rope extending in the direction of the intermediate sheave and engaging one of said idling pulleys and being continued in the direction of said other sheave and being trained over another pulley of said other sheave, said rope being 30 continued in the direction of said one sheave, means for securing said latter continuation of said rope to said one sheave, said rope being continued back and forth from said intermediate sheave to said one sheave whereby upon pulling 35 of the other end of the rope, said intermediate sheave is drawn toward said one sheave and said other sheave is pulled simultaneously with the movement of said intermediate sheave, and means engaging the rope and certain of the 40 sheaves to permit loosening of the free end of the rope while holding the one sheave and the other sheave against movement relative to each other.

2. A wire stretching means comprising a pair of 45 sheave members each including a plurality of pulleys, an intermediate sheave having a plurality of pulleys, idling pulleys carried by said intermediate sheave, a rope connecting the 50 sheaves together and means engaging the rope whereby to hold each member of said pair of sheave members against movement while permitting the intermediate sheave member to be moved relative to each of said pair of sheave members, said rope having two portions thereof secured 55

against movement to one of said sheave members, the intermediate portion of said rope being trained over the pulleys of said other sheave member, and an idling pulley of said intermediate sheave and the balance of said rope being trained over the pulleys of the intermediate sheave and the one sheave.

3. A wire stretching means comprising a pair of sheave members each having a plurality of pulleys, an intermediate sheave disposed between said pair of sheave members, idling pulleys carried by said intermediate sheave, said intermediate sheave having a plurality of pulleys and a rope engaging each of said sheave members and said idling sheave, said rope having an end secured to one of said sheave members, means carried by said one sheave member to releasably secure an intermediate portion of said rope thereto, said rope between said end and said intermediate portion being trained over the pulleys of said other sheave and an idling pulley of the intermediate sheave, means carried by said other sheave for holding the length of rope extending from said end to said other sheave whereby upon loosening of the balance of the 100 rope said intermediate sheave may be freely moved relative to either of said pair of sheaves, the remaining portion of the rope being trained over the pulleys of said intermediate sheave and said one sheave.

4. A stretching means as set forth comprising a pair of sheave members each having a plurality of pulleys, a hook carried by each sheave, an intermediate sheave having a plurality of pulleys, an idling pulley carried by said intermediate sheave, a rope engaging each of said sheaves and said idling pulley of said intermediate sheave, said rope having one end secured to a portion of one of said pair of sheave members, means carried by said one sheave member and 115 engaging the rope inwardly of said end to hold the rope against movement, that portion of the rope between the end and said holding means being trained first over a pulley of the other sheave, the idling pulley of the intermediate sheave and 120 then returned to another pulley of said other sheave, the balance of the rope being trained over the pulleys of the intermediate sheave and the pulleys of said one sheave whereby to draw said intermediate sheave in the direction of said 125 one sheave and simultaneously draw said other of said pair of sheaves in the direction of said one sheave.
